CLAIM

The ornamental design for an electromagnetic pickup for a stringed instrument, as shown and described.

DESCRIPTION

FIG. 1 is a top perspective view of an electromagnetic pickup for a stringed instrument showing my new design;

FIG. 2 is a side elevational view thereof;

FIG. 3 is a side elevational view thereof, opposite the side shown in FIG. 2;

FIG. 4 is a bottom perspective view thereof;

FIG. 5 is a top plan view thereof;

FIG. 6 is a bottom plan view thereof;

FIG. 7 is a front elevational view thereof;

FIG. 8 is a rear elevational view thereof;

FIG. 9 is a top perspective view of an electromagnetic pickup for a stringed instrument, showing a second embodiment of the design;

FIG. 10 is a top plan view thereof;

FIG. 11 is a bottom plan view thereof;

FIG. 12 is a front elevational view thereof; and,

FIG. 13 is a rear elevational view thereof.
